Term of patent 3½ years

To all whom it may concern:

Be it known that I, Frank C. Chase, a citizen
of the United States, residing at Manhasset, New
York, have invented a new, original, and orna-
mental Design for a Container, of which the fol-
lowing is a specification, reference being had to
the accompanying drawing, forming a part there-
of.

In the drawing:

Figure 1 is a top view;

Figure 2 is a side view; and

Figure 3 is another side view, with the closure
partly in section.

The essential feature of my design resides in
the particular shape of the closure.

I claim:

The ornamental design for a container sub-
stantially as shown and described.
